CLAIM

The ornamental design for an aerosol generator core as shown and described.

DESCRIPTION

FIG. 1 is a perspective view of an aerosol generator core of the present invention.

FIG. 2 is a front elevational view of the aerosol generator core depicted in FIG. 1.

FIG. 3 is a rear elevational view of the aerosol generator core depicted in FIG. 1.

FIG. 4 is a right side elevational view of the aerosol generator core depicted in FIG. 1.

FIG. 5 is a left side elevational view of the aerosol generator core depicted in FIG. 1.

FIG. 6 is a top plan view of the aerosol generator core depicted in FIG. 1; and,

FIG. 7 is a bottom plan view of the aerosol generator core depicted in FIG. 1.

The broken lines in the drawings illustrate portions of the aerosol generator core that form no part of the claimed design.
